DESIGN FOR AN ELECTRIC RAZOR BLADE SHARPENER

Kenneth F. Lees, New York, N. Y., assignor to
The Olympic Industrial Corporation, New
York, N. Y., a corporation of New York

Application July 30, 1934, Serial No. 52,739

Term of patent 3½ years

To all whom it may concern:

Be it known that I, Kenneth F. Lees, a citizen
of the United States, residing at New York, in the
county and State of New York, have invented a
new, original, and ornamental Design for an Elec-
tric Razor Blade Sharpener, of which the follow-
ing is a specification, reference being had to the
accompanying drawing, forming part thereof.

Fig. 1 is a plan view of an electric razor blade
sharpener showing my design;

Fig. 2 is a side elevational view of the same;
Fig. 3 is a left hand end view of the same; and
Fig. 4 is a right hand end view of the same.

I claim:

The ornamental design for an electric razor
blade sharpener, as shown.

KENNETH F. LEES.
